UNITED STATES PATENT OFFICE

2,149,583

CARD PUNCHING AND SLOTTING MACHINE

Edward G. Corcoran, Los Angeles, Calif., assignor to Sanford D. Buster, Jr., Sausalito, Calif.

Application April 26, 1937, Serial No. 138,878

2 Claims. (Cl. 164—111)

My invention relates to punching and slotting machinery, and more particularly to a device for slotting numerical codes on punched cards such as described and claimed in the Perkins 5 Patents Nos. 1,544,172 and 1,739,087.

My invention is also particularly adapted for punching holes in coded positions on other types of cards, as will be apparent to those skilled in the art.

10 Among the objects of my invention are: To provide a machine for slotting numerical codes on punch cards; to provide a machine which will punch or slot cards or their equivalents with apertures positioned to represent a code; to provide a machine which will consecutively slot punched cards; to provide a machine which will selectively slot code numbers on punched or unpunched cards; to provide a machine which will punch apertures in a card in pre-selected 15 positions; and to provide a simple and effective machine for coding cards for the recording of various data.

Other objects of my invention will be apparent or will be specifically pointed out in the 20 description forming a part of this specification, but I do not limit myself to the embodiment of the invention herein described, as various forms may be adopted within the scope of the claims.

The Perkins patents above referred to cover 25 a card for the recording of data thereon by punching a series of regularly positioned apertures around the edge thereof. These apertures are selectively slotted to the edge to record the desired data, so that when a stylus is passed 30 through a stack of cards all those cards which are slotted will not be picked up by the stylus, whereas those which have not been slotted in that particular location will remain on the stylus.

35 Heretofore, cards punched as described have usually been slotted by hand and the code cut through to the edge of the card with a hand punch. It is obvious that hand slotting does not lead to speed in operation nor to accuracy, and the main objective of the present invention is 40 to provide a machine which will slot codes on the punched cards with complete accuracy and in fast time.

Inasmuch as cards having numerical codes 45 slotted thereon form a large portion of the usefulness of such cards, I will describe my invention as applied to consecutive slotting of a prior punched card. Thus, each card passing beneath the device can have a different code number slotted thereon, preferably in consecutive

numerical order. However, instead of slotting the numbers into the card in numerical order, I may desire to set up any predetermined number and punch a single card with that number at one operation.

It is obvious, in the discussion herein and in the claims, that I do not wish to be limited to the actual slotting of a punched card, inasmuch as there are cards used wherein the coding is provided by the punched apertures themselves, the cards being utilized by making electrical contacts through the apertures, or by utilizing the cards as valves in a plurality of air lines, similar to the operation of a player piano roll. My invention, therefore, is deemed to apply to any cut in a card where the position determines the code, whether or not the aperture is extended to the edge of the card or is completely surrounded by card material. The word "slotting" is used herein to describe the cutting of the 20 card all the way to the edge, whereas "punching" is used to describe the formation of apertures surrounded by card material.

Broadly, my invention comprises a series of 25 adjacent and aligned slotting or punching dies, with provision for placing the card immediately beneath the dies. The dies are operated by a series of coded die wheels having a plurality of faces, the faces being cut out over a die if it is not desired that the particular die is to cut 30 the card. The faces of the wheels are not cut out over the die that is to cut the card.

Each face of the die wheel is recessed to represent a number, and when the face is brought to bear upon the upper ends of the dies, the dies 35 are forced through the card in accordance with the position of the recesses in the die wheel. I prefer to utilize a numerical system of coding, and therefore provide ten faces on each wheel, with as many wheels as there are digits in the 40 code. For example, numbers up to and including the one hundred thousands may be obtained by utilizing six wheels.

My invention may be more easily understood 45 by direct reference to the drawings:

Figure 1 is a front elevational view of a consecutive slotting machine.

Figure 2 is a plan view of a coded, punched and slotted card.

Figure 3 is a side view of the machine shown 50 in Figure 1, partly in elevation and partly in section.

Figure 4 is a planar view of the entire periphery of a recessed die wheel.

In the drawings the slotted punches, the faces 55

of the die wheels, and the counting gears, are all shown as carrying numerals; these numerals are the actual numerals of the code and are indented directly in the material of the various members, whereas the reference numerals are shown outside the members, in order to avoid confusion.

Again referring to the drawings, a die plate 1 is provided with a series of alined die apertures 2. 10 Immediately above each aperture is a slotting die 3 held in a die guide 4. Inasmuch as the slotting dies are to be positioned close together along the line of the slotting apertures, I prefer to utilize fore and aft die return springs 5 on 15 each slotting die. Each slotting die is also provided with a beveled cutting surface 6 and a hardened upper terminal 7.

Mounted immediately over the line of slotting dies is a reciprocating wheel axle 8, mounted 20 in rectangular bearings 9, the latter operating in slots 10 in side members 11 of the frame of the machine. Side members 11 are joined across the top of the machine by a top plate 12.

Mounted on the reciprocating wheel axle 8 25 are a plurality of rotatable die wheels 14, provided with ten faces 15 of equal area, each face having therein die recesses 16. The arrangement of these recesses will be explained later. Each wheel is arranged to revolve separately 30 upon the die wheel axle 8, and each wheel is provided with a thin star gear 17 which is engaged by teeth of similar gears projecting from a counting gear assembly 20. This counting gear assembly is similar to any consecutive number- 35 ing machine, and is mounted on the bearings 9 and shaft 8, being supported by counting gear arms 22. Thus, the entire set of counting gears can move as a unit with the die wheels.

The counting gear assembly 20 is preferably 40 provided with windows 24 in the front face thereof, so that the operator may see the particular number set up on the counting gears.

The counting gear assembly per se is not particularly described herein as it is no part of the 45 present invention, and is well known to all those skilled in the art.

The counting gear assembly is operated by the usual ratchet arm 25 connected to the top plate 12 by ratchet link 26. The counting gear- 50 die wheel assembly is reciprocated in a vertical plane through the medium of connecting rods 27 journaled to each end of the die wheel axle 8, and operated by crank arms 28 mounted on an overhead axle 29 driven by motor 30 through the medium of reduction gears 31.

Referring directly to Figure 2, I have shown a portion of the punched, coded card 35. The card is provided with grouped apertures 36, there being four in each group. The groups represent 60 in order units, tens, hundreds, thousands, etc. The four holes in each group are numbered 7, 4, 2 and 1 respectively, because any combination from 1 to 9 may be obtained by two cuts. For example, in the card shown, the unit group of 65 punched apertures is slotted so that the hole 1 extends to the edge of the card. The ten group has both the numeral 2 punch and the numeral 1 punch extended to the edge, thus setting up code numeral 3; the hundred group has hole 4 70 slotted out to the edge, whereas the one hundred thousand group has apertures representing 4 and 1 slotted out, giving the total number of 5. The number slotted on the card, therefore, is 500,431. This card has just been slotted by the machine, 75 leaving the machine set up for 500,432.

The manner in which the die wheel faces are recessed to slot the number desired is shown in Figure 4, the recesses being cut into the respective faces in accordance with the code. Each face of the wheel is divided into four areas, and slotting die recesses sufficiently large to receive the terminals 7 of the slotting dies are cut therein, these recesses being differently positioned on each face, and positioned in reverse of the code it is desired to cut and corresponding with the 10 code set up on the card. For example, the face of the wheel designed to slot number 1 out of the card is provided with three recesses, the face of the wheel directly over die number 1 being left untouched. Thus, when the wheel 15 is placed with that particular face over the four dies immediately below it, and the wheel is moved downwardly to engage the termini of the four dies, three of the dies representing 7, 4 and 2, will not move because their termini will enter 20 the recesses in the wheel face, whereas the die representing number 1 will be engaged by the wheel and forced downwardly through the card, which is placed in proper slotting position beneath the row of dies and spaced properly by 25 card stops 32 positioned at each end of the row of slotting dies.

As the die wheels move away from the dies the card just slotted is taken out, a new card inserted, and the unit wheel is rotated by the 30 counting mechanism so that face number 2 is presented to the dies. This face has the recesses so spaced that only the number 2 die will be carried downwardly by the wheel, and therefore the number 2 aperture in the card will 35 be slotted out to the edge. On the next stroke, number 3 face will be presented, and here there will be only two recesses in the face, so positioned that both numbers 1 and 2 dies will be carried through the card, slotting out apertures 40 2 and 1. Each reciprocation of the die wheels will bring a new face of the unit die wheel to bear against the dies, and when the unit die wheel has made one complete revolution, the next wheel, representing the tens, will rotate one 45 face, and so on, so that when the cards are changed between each reciprocation, a complete consecutive set of slotted cards is obtained, with no attention other than to feed the cards between reciprocations. This feed may be manual 50 or automatic, in accordance with printing press practice.

While I have shown my slotting device as utilized for the consecutive slotting of cards, it is obvious that with only minor changes it may 55 also be utilized for the slotting of any predetermined number. In this case the automatic counting gears may be omitted, and arrangements made for manually rotating each die wheel so that the number desired is set up on the wheels. One reciprocation is then made against an unslotted card, with the result that the card will 60 be slotted in accordance with the predetermined number.

It is further obvious that electrical or keyboard 65 arrangements may be made to rotate the die wheels into any predetermined code number, if desired. Furthermore, while I have described my device as being provided with slotting dies whereby apertures already punched in a card may 70 be slotted to the edge thereof, it is obvious that a blank card may be punched with apertures coded in any desired way, or the cards slotted without being pre-punched. This result is obtained by 75 making the slotting dies 3 with a round or other

desired contour, placing the card beneath the punches, and setting the die wheels to a predetermined number. Such cards will have apertures appearing in positions varying in accordance with the setting of the die wheels, and these cards may be used in electrical, pneumatic, or other sorting devices where coded cut cards of this character are commonly used.

5 I claim:

- 10 1. Means for cutting cards or the like in coded positions comprising a plurality of cutting dies having termini alined in a single row, a plurality of die wheels, each wheel having a plurality of planar faces, and being rotatable to present a face to one or more of said termini, said faces having recesses therein to receive one or more of said termini in accordance with a predetermined code, means for rotating each wheel to set up a combined recess code presented to said termini, means for positioning a card beneath said dies, means for reciprocating said wheels as a unit to cause certain of said termini to engage the unrecessed portions of said faces and move said engaged dies through the edge of said card to form
- 15
- 20

open slots along said edge, and means for changing the faces of said wheels presented to said termini between reciprocations.

2. Means for cutting cards or the like in coded position comprising a plurality of cutting dies having termini alined in a single row, a plurality of die wheels, each wheel having a plurality of planar faces, and being rotatable to present a face to one or more of said termini, said faces having recesses therein to receive one or more of said termini in accordance with a predetermined code, means for rotating each wheel to set up a combined recess code presented to said termini, means for positioning a card beneath said dies, means for reciprocating said wheels as a unit to cause certain of said termini to engage the unrecessed portions of said faces and move said engaged dies through the edge of said card to form
